Patented Feb. 24, 1914.

UNITED STATES PATENT OFFICE.

ISAAC KESSLER, OF PHILADELPHIA, PENNSYLVANIA.

VEST.

1,088,285.

Specification of Letters Patent.

Patented Feb. 24, 1914.

Application filed January 28, 1913. Serial No. 744,612.

To all whom it may concern:

Be it known that I, ISAAC KESSLER, a citizen of the United States, residing at Philadelphia, in the county of Philadelphia and 5 State of Pennsylvania, have invented certain new and useful Improvements in Vests, of which the following is a specification.

My invention relates to improvements in vests, and more particularly to vests or 10 waistcoats worn by gentlemen, the object of the invention being to so construct the garment that it will conform to the shape of the body and neatly fit the figure without the necessity for the ordinary strap and 15 buckle commonly employed at the back of the garment.

A further object is to provide an improved construction and arrangement of elastic strips confined between the lining 20 and the back of the garment, secured to the back of the garment and causing the garment to be elastically drawn at both sides of the center of the back, so as to compel the garment to conform in shape to the 25 shape of the figure.

With these and other objects in view, the invention consists in certain novel features of construction and combinations and arrangements of parts as will be more fully 30 hereinafter described and pointed out in the claim.

In the accompanying drawings: Figure 1 is a rear view of a vest embodying my improvements. Fig. 2 is a fragmentary view 35 with a portion of the lining of the vest broken away and showing the vest extended to full width. Fig. 3 is an exaggerated view in longitudinal section on the line 3—3 of Fig. 2, and Fig. 4 is a view similar to 40 Fig. 3 showing the vest as it is drawn in by the elastic strips.

In constructing my improvements, I secure at the waist line of the garment, two elastic strips 1, 1, which are sewed to the 45 back 2 of the garment by rows of stitching 1' adjacent the upper and lower edges of the strips 1, and at their ends are sewed to inelastic strips 3. These strips 3 are in turn sewed at their ends in the seams of the garment as indicated in Figs. 3 and 4.

For clearness of description, I shall give the front material the reference numeral 4,

and the lining for the front the reference numeral 5.

The back 2 and the back lining 6 are 55 made in two pieces seamed together down the center as indicated at 7, and to the seam 7, the adjacent ends of the inner strips 3 are secured. In other words, the ends of the inner strips 3 are sewed in with the 60 seam. The outer ends of the outer strips 3 are sewed in with the seams 8 which connect the back and front, and back and front linings as indicated clearly in Figs. 3 and 4. It will therefore be noted that between the 65 back and the lining of the vest, I locate two strips 1 of elastic which are connected to the seams at the center and at the sides by strips of inelastic material 3. Furthermore, the elastic strips 1 are secured directly to 70 the back 2 by lines of stitching. This stitching is done when the elastic strip is extended as indicated in Fig. 3, so that when the elastic strip contracts, it gathers the material of the back 2 as indicated in Figs. 1 75 and 4. As the back 2 and the lining 6 for the back are of practically the same size, when the back is gathered, the lining will remain more or less smooth, at least, it will not be apparently gathered at any particular point. 80 The vest is therefore capable of an extension at the waist equal to the maximum size of the back and the lining, and will fit any figure from such maximum to the minimum, and remain smooth on the figure. 85 The strain of the elastic strips 1 is taken up by the inelastic strips 3, and is therefore distributed so that there is no tendency to break the binding threads.

Various slight changes might be made in 90 the general form and arrangement of parts described without departing from my invention, and hence I do not limit myself to the precise details set forth, but consider myself at liberty to make such changes and 95 alterations as fairly fall within the spirit and scope of the appended claim.

Having thus described my invention, what I claim as new and desire to secure by Letters Patent is:

A vest having a back, a front, side seams connecting said back to said front, linings for the front and back, elastic strips secured to the inner face of the back by rows of

stitching arranged adjacent the edges of the strips, and normally holding the back gathered, and inelastic strips secured to the ends of the elastic strips and attached at 5 their ends to the seams of the vest, all of said strips being arranged between the back and the back lining, substantially as described.

In testimony whereof I have signed my name to this specification in the presence of 10 two subscribing witnesses.

ISAAC KESSLER.
